APPARATUS FOR THE MANUFACTURE OF
CONCRETE PIPE

George W. Kopp, Hicksville, N. Y.

Application October 21, 1936, Serial No. 106,747

15 Claims. (Cl. 25—30)

This invention relates to improvements in apparatus for making concrete pipe by centrifugal processes.

Large amounts of concrete pipe, both plain and reinforced, are successfully made by such processes. The molds are filled with concrete and rotated by machines which cause the concrete to be formed into a pipe in a very short period of time. It is a long time after the pipe and mold are removed from the machine, however, before the mold can be stripped from the pipe and used again.

Each mold is lined with a thin layer of wax before being filled with concrete. After a pipe has been formed, the mold is put in a steam-heated kiln which cures the concrete and melts the wax so that the pipe is not tight in the mold, and the mold can be removed from the pipe, cleaned, and prepared for use again. Large pipes remain in the kiln for many hours and each mold can therefore be used only once or twice a day. This makes a large number of molds necessary and materially increases the cost of the pipe by requiring excessive capital investment in molds and kiln equipment.

It is an object of this invention to provide improved mold equipment for making concrete pipe by centrifugal processes. One of the advantages of my improved mold is that it can be stripped from the pipe immediately after it comes from the mold-rotating machine and before the pipe has been cured. This makes it possible to put the mold back into use on the machine without delay.

The economic advantages of the new design are found in the great reduction in capital investment from that required for the solid or one-piece forms of the usual type, saving of fuel necessary to generate steam for curing, the saving of expense for wax, the much less kiln equipment required, and a general speeding up of production.

Other features of the invention relate to the use of the same mold for pipes of different size by changing an inner shell which holds the concrete; to the support of the concrete pipes while they are being cured; and to the retention of moisture in the mold during the spinning operation.

Other objects, features and advantages of the invention will appear or be pointed out as the specification proceeds.

In the accompanying drawings, forming part hereof:

Fig. 1 is a diagrammatic view of apparatus for making concrete pipe by a centrifugal process;

Fig. 2 is a longitudinal sectional view through a mold made in accordance with this invention;

Fig. 3 is an enlarged transverse sectional view taken on the line 3—3 of Fig. 2;

Fig. 4 is an enlarged fragmentary, transverse sectional view taken on the line 4—4 of Fig. 2;

Fig. 5 is a bottom plan view of the seam cover plate on a reduced scale; and

Fig. 6 is a reduced-scale diagram illustrating the operation of the invention.

Apparatus for making centrifugal pipe is shown diagrammatically in Fig. 1, and comprises a mold 11 having a running ring 12 by which one end of the mold is supported from rollers 13. The other end of the mold 11 has a similar ring 14 which may be supported on rollers, or held in a chuck 15 of the spinning and troweling machine. The chuck 15 is carried by a shaft 17 journaled in a bearing 18 and driven through speed reduction gearing 19 by a motor 20.

Concrete is put into the mold 11 by a trough 22, the end portion of which is shown to the right of the mold in Fig. 1. The trough enters the mold and extends for the full length of the mold. After being pushed all of the way into the mold the trough is rotated and dumps the concrete which it contains into the mold. The trough is then moved into a position where one of its edges bears against the concrete as a trowel to spread it evenly and dress its inside surface. The mechanism for moving the trough 22 is not shown in Fig. 1 because it is not necessary to a complete understanding of this invention.

The mold 11 may be constructed as shown in Fig. 2. Running rings 12 and 14 are rigidly connected to opposite ends of longitudinal structural members comprising channels 25. These channels are angularly spaced around the rings 12, 14 and are fastened to the rings by screws 27 extending through end plates 28 welded to the ends of the channels. The screws 27 thread into the sides of the running rings. On small-size molds designed to have one end always supported by a chuck, the running ring 14 may be replaced with an end casting of smaller diameter than the running ring for insertion in the jaws of a chuck. The running rings 12 and 14 are solid. In molds having running rings split to permit the mold to open, the rings always get flat spots, after continued use, at the line where the surfaces come together.

The running ring 14 is recessed to receive a spigot end ring 29, which is held in place by screws 30 threading into the running ring. Steel hoops 31 passing around the channels 25 and con-

nected to the channels by angles 32 prevent the channels from being bowed by centrifugal force when the mold is spinning.

An end member 34 is recessed into a face of 5 the running ring 12 and welded to that ring. The running rings 12 and 14, spigot end ring 29, channels 25, hoops 31, end member 34, and their respective fastenings comprise a rigid frame which is the runner or carrier form of the im- 10 proved mold shown in the drawings.

The channels 25 are made thicker at spaced 15 points along their length by welding nuts 36 to the webs of the channels. Holes through the channels in alinement with the holes through the nuts 36 are tapped to receive pressure screws 38. The end member 34 has threaded holes in line 20 with the channels 25 for receiving pressure screws 38', which may be of somewhat smaller size than the pressure screws 38.

An inner form or shell 42 is constructed of 25 resilient sheet metal or thin plate, and it is this inner form 42 that holds the concrete. The inner form 42 is split and has edges 43 abutting along a longitudinal seam 44, shown at the bottom of 30 the form in Fig. 3.

A cover plate 46 is connected to the shell 42 by rivets 47, 48 (Figs. 3 and 4) along one side of the seam 44 and this cover plate extends across the seam to prevent the escape of water from inside 35 the shell when the form is rotating. That side of the cover plate 46 which is not riveted to the shell 42 is held against the shell by buttons 50 (Fig. 4) which have stems 51 with reduced ends threaded into the shell. The stems 51 extend 40 through slots 52 in the cover plate 46. These slots are best shown in Fig. 5. The cover plate is free to slide circumferentially with respect to the buttons 50.

Referring again to Figs. 2 and 3, the shell 42 45 has lugs 55 riveted to it close to the pressure screws 38. A portion of each lug 55 is spaced from the surface of the shell 42 and has a slot through which the cooperating pressure screw 38 extends. Each of the pressure screws has a block 50 57 pinned or otherwise secured to its inner end. These blocks 57 pull against the lugs 55 to expand the shell 42 when the pressure screws are turned in a direction to back them away from the shell. When the pressure screws are turned the other 55 way, the blocks 57 serve to increase the area of contact for the pressure screws 38 against the shell. The pressure screws are in effect means reacting between the carrier form and the inner shell to hold the inner shell to a substantially circular contour and to prevent distortion of the inner shell by centrifugal force when the mold is being turned during the centrifugal operation of forming a pipe within the shell.

The shell 42 can be removed from the carrier 60 form by relaxing the pressure of the screws 38 and then causing relative rotation of the shell 42 and carrier form so that the screws 38 move beyond the ends of the slots in the lugs and leave the shell free to move axially out of the carrier frame.

Inner forms or shells of different diameter can 65 be put in the outer or carrier form in place of the shell 42. The limits on the shell sizes which can be accommodated in the carrier form shown in the drawing depends upon the inside diameter of 70 the running rings 12, 14 and upon the length of the pressure screws 38.

A centering ring 59 fits within the spigot end 75 of the shell 42. This ring is preferably annular to permit access to the inside of the mold for measuring. With large size molds using a wet

mix, the centering ring 59 is replaced with a solid disk to prevent water from being thrown out of the mold.

An end former ring or pallet 61 fits into the bell 5 end of the shell 42 and has a shoulder abutting against the end of the shell. The pallet 61 is firmly clamped in the shell when the pressure screws 38' are turned down into contact with the shell, but further insurance against displacement of the pallet is obtained by holding a clamp- 10 ing ring 63 against the end face of the pallet.

The clamping ring 63 is held against the end member 34 and the pallet 61 by wedges 65 driven through pins 66. These pins extend through the end member 34, and the wedges 65 provide a 15 quicker means for fastening and unfastening the clamping ring than if bolts were used in place of the pins 66.

Fig. 6 shows the manner in which the mold or shell 42 is stripped from a concrete pipe 68. The 20 pressure screws 38 along the seam 44 are turned to back them away from the pipe 68. These pressure screws pull both edges of the shell away from the pipe because the cover plate over the seam will not permit either edge of the shell 42 25 to move outward without moving the other. This is clear from Fig. 4, which illustrates how the rivets 48 hold the plate 46 against the shell 42 on one side of the seam and the buttons 50 hold the plate against the shell on the other side of the 30 seam. As the shell is pulled away from the pipe it is, of course, necessary for the edges of the seam 44 to move apart, and such movement is possible because of the fact that the stems 51 of the buttons extend through slots 52 which permit relative 35 movement of the plate 46 and the stems 51. The cover plate 46 is omitted from Fig. 6 in order to make the diagram clearer and to show the separation of the seam edges.

After the pressure screws 38 along the seam 44 40 have been operated to pull the adjacent portions of the shell 42 away from the pipe 68, the pressure screws along the two channels 25 next nearest to the seam 44 are backed away from the pipe to pull more area of the shell 42 out of contact with 45 the pipe.

As each pressure screw 38 is operated to pull the portion of the shell beneath it away from the pipe 68, the stiffness of the shell causes it to pull away from the pipe over considerable area beyond 50 that screw so that after the pressure screws along the seam and those along the next channel on each side of the seam have been operated to pull the shell 42 away from the pipe 68, more than half 55 of the surface of the shell is out of contact with the pipe and the mold can be freely removed from the pipe unless stuck to the pipe.

If the shell sticks to the pipe, more pressure screws can be backed away from the pipe to pull the shell loose, but such sticking of the pipe and 60 shell is not ordinarily encountered, and with mixes or molds where it does occur it can be avoided by greasing the inside surface of the shell before filling it with concrete.

The mold is preferably stripped from the pipe 65 with the pipe in an upright position and the pallet 61 at the lower end of the pipe. The clamping ring 63 is removed before the mold and pipe are turned upright and the mold is then lowered to rest the pallet on some supporting surface. The pressure screws 38 are operated to loosen the shell 42 from the pipe in the manner already described. The backing-off of the screws 38' releases the pallet 61, and since the pallet is removable longitudinally the mold can be lifted from the 70 pipe.

pipe, leaving the pipe resting on the pallet, which serves as a support for the freshly made pipe when placed in the curing room. Thus the entire mold, with the exception of the pallet, is removed as a unit from the pipe, and the mold is made ready to use again immediately by returning the pressure screws to their original positions and replacing the pallet. A new pallet is put on the mold for making the next section of pipe because the curing operation requires a substantial length of time.

This invention has been described in connection with the manufacture of concrete pipe, but it will be understood that the invention can be used for making other hollow objects of concrete or other agglomerate. The invention is not limited to the particular structural embodiment which has been illustrated and described, and features of the invention may be used without others.

I claim:

1. A form for the centrifugal manufacture of concrete pipe or the like, said form comprising a split inner form which holds the concrete during the spinning operation, a permanently integrated frame surrounding said inner form, and means on the frame adapted to connect with the split inner form and operable to pull at least a part of said inner form away from the surface 30 of a pipe to facilitate stripping of the form from the pipe.

2. Improvements in forms for the manufacture, centrifugally, of concrete pipe or the like, comprising a split sheet metal inner form surrounded by a rigid running form with bolts extending between the forms, and connections between the bolts and inner form for spreading the inner form to strip it from a pipe.

3. A form for making concrete pipe or the like by a centrifugal process, said form comprising a split, resilient, inner form in which the concrete is held during spinning operation, a rigid, outer form adapted to be supported by the spinning apparatus, connecting means between the inner and outer forms for expanding the inner form to pull it away from the surface of a pipe made in said inner form, the connecting means including lugs on the outside of the inner form, and screws held by said lugs and extending 50 through the outer form.

4. A form for the manufacture, centrifugally, of concrete pipe or the like, comprising a resilient inner shell for holding the concrete, said inner shell having abutting edges forming a seam lengthwise of the inner shell, a frame surrounding and spaced from the inner shell, a plurality of pressure screws extending through the frame into contact with the outside of the inner shell at points spaced lengthwise of and angularly 55 around the shell to prevent any substantial distortion of the shell by centrifugal force, and lugs on the outside of the shell in positions to be pulled toward the frame to expand the shell and strip it from the pipe when the screws are turned 60 in one direction.

5. A form for the manufacture, centrifugally, of concrete pipe or the like, comprising a resilient inner shell for holding the concrete, said inner shell having abutting edges forming a seam lengthwise of the inner shell, a frame surrounding and spaced from the inner shell, said frame including end rings connected by a number of angularly-spaced, longitudinal structural members, screws extending through each of said members at spaced points along its length and into

contact with the resilient inner shell to hold it against distortion by centrifugal force, and lugs secured to the shell under each of the screws in position to be pulled outward when the screw is turned in a direction to back it away from the shell.

6. A mold for the manufacture of concrete pipe or the like by the centrifugal process, including in combination a carrier form adapted to be rotated, a split shell in the carrier form for holding the concrete, an end former ring detachably held at one end of the shell, and means for stripping the mold from a pipe including devices on the carrier form operable to release the shell from the pipe when the mold is 15 in an upright position with the former ring under the lower end of the pipe, said former ring serving as a support on which the pipe can rest during the curing operation.

7. Apparatus for the centrifugal manufacture 20 of concrete pipe or the like, including a runner form, an inner mold carried in the runner form and adapted to hold the concrete, said inner mold being expansible radially of the pipe to strip said mold from the pipe, means on the runner form operable to cause such expansible movement of the inner mold, and a pallet at one end of the inner mold for forming one end of the pipe, said pallet being longitudinally releasable from the mold so that the pipe can rest on the 30 pallet after the mold has been stripped from the pipe with the pipe in an upright position.

8. Improvements in molds for manufacturing, centrifugally, concrete pipe or the like, comprising a carrier form having one or more solid running rings for supporting the form on rotating rollers, a split mold within the carrier form, and means on the carrier form for holding the mold closed while rotating the pipe and for stripping the mold from the pipe after the spinning opera- 40

9. A mold for making concrete pipe or the like by a centrifugal process, comprising a runner form with longitudinally extending frame members angularly spaced around the form, a split shell within the runner form, pressure screws threaded through the frame members at points along the length of the shell and extending radially into contact with the shell to hold said shell to a circular contour and hold the seam edges 50 in substantial abutment, and a cover plate over the seam to prevent the escape of water from within the shell during a spinning operation.

10. A mold for making concrete pipe or the like by a centrifugal process, comprising a runner form with longitudinally extending frame members angularly spaced around the form, a split shell within the runner form, lugs attached to the shell and having portions spaced from said shell and with slots extending circumferentially with respect to said shell, means carried by the frame members and extending through said slots to hold the shell against axial movement in the runner form, the shell being axially removable from the runner form by causing relative rotary movement of the shell and form to release the lugs from the means extending through the slots in the lugs, said means being radially adjustable toward and from the shell to accommodate a shell of different size within the 60 runner form.

11. A form for the centrifugal manufacture of concrete pipe or the like, said form comprising a rigid outer frame structure having one or more running rings, a split inner shell within the outer 75

frame structure for holding the concrete during the spinning operation, and means for expanding the split shell while the rigid outer frame remains unaltered, said means including devices carried by the outer frame and extending inward to the split inner shell.

12. A form for the centrifugal manufacture of concrete pipe or the like, said form comprising a rigid carrier form with one or more running rings, a split mold comprising a shell that holds the concrete, said mold being located within the carrier form, and means on the carrier form which contact with the split mold at several angularly spaced points around its outside surface to hold the mold closed and substantially cylindrical in shape during the centrifugal operation of forming a pipe within the mold, said means reacting between the carrier form and the split mold and being movable with respect to the carrier form to permit the mold to be stripped from the pipe.

13. A form for the manufacture, centrifugally, of concrete pipe or the like, comprising a one piece, sheet metal inner shell for holding the concrete, said inner shell having longitudinally extending edges movable circumferentially with respect to one another to expand the inner shell when a pipe is to be removed from the mold, a frame surrounding and spaced from the sheet metal inner shell, a plurality of pressure devices on the frame extending into contact with the outside of the sheet metal shell at points spaced lengthwise of and angularly around the shell to give the shell a substantially circular contour and to prevent any substantial distortion of the shell

by centrifugal force, and lugs on the outside of the shell in positions to be pulled toward the frame to expand the shell and strip it from the pipe when the pressure devices are moved in one direction.

14. A composite form for the centrifugal manufacture of concrete pipe or the like, said form comprising a rigid outer frame structure having one or more running rings, a split inner shell within the outer frame structure for holding the concrete during the spinning operation, and means holding the outer frame and inner shell in assembled relation, said means including devices carried by the outer frame and extending inward to the split inner shell and operable to expand the split inner shell while the rigid outer frame remains unaltered.

15. A composite form for the centrifugal manufacture of concrete pipe or the like, said form comprising a rigid outer frame structure having one or more running rings, a resilient inner shell within the outer frame structure for holding the concrete during the spinning operation, said resilient shell being split lengthwise to permit it to open when a pipe is to be removed from the mold, and means holding the outer frame and inner shell in assembled relation, said means including several devices reacting between the outer frame and the resilient inner shell at spaced apart points around the peripheral surface of the resilient inner shell, to give said resilient shell a substantially circular contour and to prevent any substantial distortion of the shell by centrifugal force.

GEORGE W. KOPP. 35
